United States Patent Office

Des. 180,947
Patented Sept. 10, 1957

180,947

HAT

Rosa M. Fry, Columbus, Ga.

Application June 4, 1956, Serial No. 41,750

Term of patent 7 years

(Cl. D3—13)

Fig. 1.

Fig. 2.

Fig. 3.

Fig. 4.

The essential features of my design reside in the portions shown in solid lines on the drawing.

What I claim is:

The ornamental design for a hat, as shown and described.
